United States Patent Office.

DAVID CHRISTIE, OF CHILLICOTHE, OHIO.

Design No. 4,811, dated April 18, 1871.

DESIGN FOR A CLAW-BAR.

The Schedule referred to in these Letters Patent and making part of the same.

I, DAVID CHRISTIE, of Chillicothe, Ross county, Ohio, have invented and produced a new and original Design for a "Claw-Bar," of which the following is a specification.

The nature of my design is fully represented in the accompanying drawing.

Claim.

I claim as my invention—

The design for a claw-bar, as shown.
In testimony of which invention I hereunto set my hand.

DAVID CHRISTIE.
